Attorney

UNITED STATES PATENT OFFICE

HARRY VAN DORIN, OF SHELBYVILLE, INDIANA

HOLDER FOR CHRISTMAS TREES AND THE LIKE

Application filed July 11, 1928. Serial No. 291,747.

The present invention relates to devices for holding in upright position Christmas trees, flagstaffs and other devices of the same general character.

5 The object is to provide a simple structure of a novel character that can be dismembered and can be packed in relatively little space. The structure, however, when assembled, constitutes an effective and ornamental support 10 or base.

A further and important object is to provide parts that can be easily and cheaply manufactured.

In the accompanying drawings:

15 Figure 1 is a perspective view of the support in assembled position.

Figure 2 is a detail view showing the cup member and one of the legs therefor in a position to be separated.

20 Figure 3 is a sectional view showing a leg in its locked position.

Figure 4 is a top plan view of the cup member.

25 Figure 5 is a detail sectional view on the line 5—5 of Figure 3.

In the embodiment disclosed, a body is employed in the form of a cup member 6 having side walls 7 and a bottom 8. This provides a chamber 9 for the lower end of a Christmas 30 tree or other article, and in the case of a tree, the chamber may be filled with water to prevent the withering of the tree. This cup member is provided at its upper end with sets of outstanding inwardly turned hooks 10, 35 three of said sets being shown. The bottom is provided with three outstanding hooks 11 having downturned bills 12. These hooks 11 are located in vertical planes that pass between the hooks 10 of the upper sets.

40 Three legs are provided in the present form of structure. These legs are formed of sheet metal straps that preferably have some resiliency. Their lower portions 13 are outwardly bowed and provided with inturned lower feet 14. Their central portions 15 are vertically disposed and extend alongside the body or cup member 6. Their upper portions extend above said body or cup member 6, and are bowed inwardly as shown at 16 above the 45 open top of said cup member. The central

portions 15 of the legs are provided with lower elongated openings 17 through which the hooks 11 are adapted to be passed. The upper ends of said portions 15 are reduced in the form of upwardly tapered wedges 18, 55 the upper ends of which are adapted to pass between the hooks 10 of the upper sets, the lower portions, however, being wider than the spaces between the hooks of said sets. As will be clear by reference to Figure 2 60 the legs and body are assembled by passing the hooks 11 through the slots 17 and correspondingly passing the narrower portions of the wedges 18 between the hooks 10 of the upper sets, then moving the body 6 downwardly, thereby causing the bills 12 of the lower hooks to engage over said legs and the wedges 18 to engage between the upper hooks. A rigid structure is thus produced, in which 65 the weight of the article placed in the body serves to more firmly lock the parts together. When thus assembled and as indicated in Figure 1, a tree trunk, staff or other article introduced into the chamber 9 of the body or cup member will rest therein and at the same time 70 be braced by the inwardly bowed portions 16 of the legs, which will yieldingly grip the same. To remove the parts it is only necessary to slide the legs downwardly or the body 75 upwardly on said legs, whereupon the latter 80 can be readily detached and the parts nested.

From the foregoing, it is thought that the construction, operation and many advantages of the herein described invention will be apparent to those skilled in the art, without further description and it will be understood that various changes in the size, shape, proportion and minor details of construction may be resorted to without departing from 85 the spirit or sacrificing any of the advantages of the invention.

What I claim is:

1. In a device of the character set forth, a staff holder, a supporting leg member having an opening, a hook carried by the staff holder and engaged in the opening, and a hook carried by the staff holder and engaging around an edge of the leg member.

2. In a device of the character set forth,

a staff holder, a supporting leg member having an opening, a hook carried by the staff holder and engaged in the opening, and oppositely disposed hooks carried by the staff holder, said leg members having a wedged shaped portion whose narrow part can pass between the hooks and whose wider part will be embraced by said hooks.

3. In a device of the character set forth, a staff holder, a supporting leg member having an opening, a hook carried by the staff holder and engaged in the opening, and oppositely disposed hooks carried by the staff holder, said leg member having a wedged shaped portion whose narrow part can pass between the hooks and whose wider part will be embraced by said hooks, said leg member having a yielding portion extending above the holder to engage a staff placed in said holder.

4. In a device of the character set forth, a staff holding cup having a plurality of downturned hooks at its lower end and sets of oppositely inturned hooks at its upper end, and leg members that extend below and above the cup, said leg members having openings that receive the downturned hooks and having upwardly tapered wedge portions that fit between the hooks of the upper sets, the upper ends of the leg members constituting yielding bearings against the sides of a staff placed in the cup.

In testimony whereof, I affix my signature
HARRY VAN DORIN.
